No. 794,083.

PATENTED JULY 4, 1905.

H. H. CUSHMAN.
CARBONATING APPARATUS.
APPLICATION FILED MAR. 2, 1905.

UNITED STATES PATENT OFFICE.

HUBERT H. CUSHMAN, OF BALTIMORE, MARYLAND, ASSIGNOR OF ONE-HALF TO JAMES D. BROWN, OF BALTIMORE, MARYLAND.

CARBONATING APPARATUS.

SPECIFICATION forming part of Letters Patent No. 794,083, dated July 4, 1905.

Application filed March 2, 1905. Serial No. 248,082.

To all whom it may concern:

Be it known that I, HUBERT H. CUSHMAN, of Baltimore, in the State of Maryland, have invented certain new and useful Improvements in Carbonating Apparatus; and I hereby declare that the following is a full, clear, and exact description thereof, reference being had to the accompanying drawings, which form part of this specification.

- 10 This invention is an improved apparatus for carbonating liquids or charging liquids with gas; and its objects are to enable the carbonating process to be carried on continuously, if desired; to maintain a supply of the carbonated liquid; to expedite the carbonation by producing mechanical stirring of the gas and liquid within a closed chamber; to utilize the gases or liquid, or both, as the means for actuating the mechanical stirrers; to arrange the
- 20 stirrers wholly within the chamber in which the mixing is effected without passing any part thereof through the walls of such chamber, thus avoiding any possibility of leakage at the bearings of the moving parts, and to
- 25 utilize the stirrers as the means for admitting the liquid and the gas in minute sprays or jet into the mixing-chamber.

The invention will be fully understood from the following detailed description of the apparatus illustrated in the accompanying drawings, which shows an apparatus designed particularly for carbonating water for soda-fountains or other dispensing apparatus; but the invention is not restricted to such specific apparatus, as the form, dimensions, and number of parts can be varied within the scope of the invention to suit the particular requirements of the user, and I therefore refer to the claims for summaries of the essential features and combinations of parts embraced in the invention.

In said drawings, Figure 1 is a vertical sectional view of a carbonating apparatus embodying the invention. Fig. 2 is a horizontal section thereof on line 2 2, Fig. 1. Fig. 3 is an enlarged vertical section through one of the agitator spray-heads. Fig. 4 is a horizontal section on line 4 4, Fig. 3.

A designates a vessel of any suitable form and dimensions closable both gas and water

tightly. It may be provided with a water-gage *u* to show the height of fluid therein, a pressure-gage *u'*, an air-valve *a*, and a draw-off pipe *A'*. Within this vessel is a tubular standard *B*, closed at its inner end, but opening through the base, so that the gas-supply pipe *G* and water-supply pipe *W* may be introduced therewith. Mounted on this standard *B* within the vessel are rotatable rings *C*, which may be provided on their inner faces with channels *g* and *w*, as shown in Fig. 3. The channel *w* connects with a branch of the water-pipe *W* within the standard, as shown at *w'* in Fig. 3, and the channel *g* connects with a branch of the gas-pipe *G*, as shown at *g'*. Consequently the channels *g* and *w* may be constantly supplied with gas and water, respectively.

Tapped into the collar *C* and communicating with channel *w* are laterally-perforated tubular arms *W'*, through which water can escape into the vessel *A*, and similarly tapped into the said collar are arms *G'*, which are laterally perforated to allow gas to escape into said vessel. The reaction of the escaping jets of gas and water will cause the collar and arms to revolve within the vessel, as is well understood, and the submerged arms and collars will act as stirrers or agitators to maintain the thorough impregnation of the liquid with the gases, while the unsubmerged arms will deliver gases and water in the rotary sprays or jets, which will insure the most rapid absorption of the gas by the liquid. If the vessel becomes full of water, gases can still be forced therein and will cause rotation of the arms and consequent agitation of the water and commingling of the gases therewith in the most efficient manner. Introducing the gas in the form of sprays or jets from separate arms I consider a valuable feature of the invention, and as I do not attempt to mingle the gases and water in the supply-pipe consequently I can regulate the relative amounts of gas and air and water with the greatest precision, the introduction of the gas into the body of liquid by means of spray-heads or jet-heads moving through the water being very effective and rapid in results.

The gas-pipe may be connected direct to a

liquid carbonic-gas container and the water-pipe connected to a suitable supply under pressure or to a pump which can force the liquid into the vessel against the gas-pressure 5 therein, which is ordinarily about one hundred and fifty pounds. The carbonated water 10 may be withdrawn through the pipe A', and it is possible with this apparatus to maintain a practically constant supply of carbonated 15 water of uniform strength or liveliness.

If desired, the water-pipe W may be also connected with a spray head or nozzle W', arranged in the top of the vessel, so that water can be dropped in a shower through the free 15 gas in the upper part of the vessel, which would facilitate initial carbonation of the water.

Having thus described my invention, what I claim as new, and desire to secure by Letters 20 Patent, is—

1. In combination, a hollow water-holding vessel, a hollow standard therein, a series of radially-extending hollow arms rotatably connected with said standard at different levels, 25 and means for admitting fluids into said vessel through said arms, whereby the arms are caused to rotate in the vessel and act as stirrers.

2. In a carbonating apparatus, the combination of a hollow water-holding vessel, a hollow standard therein, a series of rings rotatably mounted on said standard, one above the other, a series of radially-projecting hollow perforated arms attached to said rings, 35 and means for supplying gas through the standard to said rings and arms, for the purpose and substantially as described.

3. In a carbonating apparatus, the combination of a closed vessel, two series of revolvable hollow arms or stirrers therein, arranged below the liquid level, means for supplying liquid to one series of arms, and means for supplying gas to the other series of arms.

4. In a carbonating apparatus, the combi-

nation of a closed vessel, a central hollow standard and therein, sets of laterally-perforated arms or stirrers revolvably mounted on said standard, means for supplying liquid to some of said arms, and means for supplying gas to the other arms.

5. In a carbonating apparatus, the combination of a closed vessel having a central hollow standard, a series of revoluble channeled rings mounted on said standard within the vessel, radially-extending perforated arms attached to each of said rings, means for conducting water through the standard to some of said rings, and means for conducting gas through the standard to other of said rings.

6. In a carbonating apparatus, the combination of a closed vessel, a tubular standard in said vessel, a plurality of revoluble rings mounted on said standard, perforated arms connected to said rings, a water-supply pipe communicating with all of said rings to supply water to part of the arms and a gas-supply also communicating with said rings to supply gas to the other arms.

7. In a carbonating apparatus, the combination of a closed vessel, a tubular standard in said vessel, revoluble rings mounted on said standard having two internal channels; sets of perforated arms connected to said rings and respectively communicating with one of said channels, a water-supply pipe communicating with one channel of said rings to supply water to part of the arms thereon, and a gas-supply communicating with the other channels in said rings to supply gas to the other arms on said rings.

In testimony that I claim the foregoing as my own I affix my signature in presence of two witnesses.

HUBERT H. CUSHMAN.

In presence of—

JAMES D. BROWN,
ARTHUR E. DOWELL.
